SNOW GLIDER OR SKI

Einar Wennerstrom, East Rochester, N. Y.

Application May 5, 1938, Serial No. 206,254

1 Claim. (Cl. 280—11.13)

My invention relates generally to means of locomotion over snow covered surfaces, and particularly to a snowglider or ski wherein means is provided on the bottom thereof of preventing back-sliding of the snowglider or ski on an up-hill climb or stop, and an important object of my invention is to provide efficient and practical arrangements of this character.

Other important objects and advantages of my invention will be apparent from a reading of the following description taken in connection with the drawings, wherein for purposes of illustration I have shown a preferred embodiment of my invention.

15 In the drawings:

Figure 1 is a general top plan view of a ski or snowglider in accordance with the present invention.

Figure 2 is a bottom plan view of Figure 1.

Figure 3 is a right hand side elevational view of Figure 1.

Figure 4 is an enlarged fragmentary bottom plan view of Figure 1.

Figure 5 is an enlarged fragmentary side elevational view of Figure 1.

Figure 6 is a transverse vertical sectional view taken through Figure 1 approximately on the line 6—6.

Figure 7 is a longitudinal vertical sectional view taken through Figure 1 and showing the arrangement of the inserts.

Referring in detail to the drawings, the numeral 5 generally designates the ski or snowglider which has the general outline and form of a conventional ski or snowglider including on its top the foot accommodating portion 6 intermediate its ends into which merge the concavo-convex longitudinal portions 7 and 8 which are convexed on their undersides as indicated by the numeral 9 in Figure 6. The groove 9 extends substantially the full length of the ski or snowglider providing on its opposite sides the snow engaging surfaces 10 and 11 above which are the lateral longitudinal grooves 12 and 13.

40 In accordance with the present invention the snow engaging surfaces 10 and 11 are provided at unequal intervals with inwardly extending step-cuts 14, 15, respectively, the step-cuts on the

opposite sides of the groove 9 being staggered with their working faces 16 close together on the opposite sides of the groove 9 as illustrated to advantage in Figure 4 of the drawings. These step-cuts, as shown in Figure 7, have the large end 5 to the front of the ski or snowglider, and a triangular cross-section continuation 17 of the step-cuts, which continuation leads into the particular ground engaging elements 10, 11 in an upward and forward inclination and therein is fixed in 10 some suitable manner a wedge 18 of suitable long lasting material, such as hardwood which presents a substantially right angular shoulder 19 at the highest point of the step-cut to provide purchase on the packed snow as the weight of the wearer 15 is placed on the snowglider or ski, so as to positively prevent backsliding in either climbing or standing. As shown in Figure 2 of the drawings, the first step-cut is located somewhat to the rear of the front termination of the groove 9, while 20 the last step-cut is located close to the rear end of the groove 9. It is to be observed that the inserts 18 have their laterally inward terminals of the portion 19 extended laterally inwardly just over the edges of the groove 9, thereby providing 25 a better purchase on the snow during forward locomotion as well as in climbing and in standing upon a backsiding incline.

Although I have shown and described herein a preferred embodiment of my invention, it is to 30 be definitely understood that I do not desire to limit the application of the invention thereto, and any change or changes may be made in the materials and in the structure and arrangement of the parts, within the spirit of the invention and the 35 scope of the subjoined claim.

Having described the invention, what is claimed as new is:

In a snowglider, a body formed on its bottom with substantially parallel sliding surfaces, said 40 surfaces being formed with step-cuts at longitudinal intervals, each step-cut defining a rearwardly facing shoulder for pushing rearwardly against snow in the step-cut, said shoulder being formed with a slot, and a durable material insert in said 45 slot and exposed on said shoulder.

EINAR WENNERSTROM.
